ASSIGNORS TO S. F. BOWSER & COMPANY, INCORPORATED, OF FORT WAYNE,
INDIANA.

WASTE-SOAKING TANK.

1,153,690.

Specification of Letters Patent. Patented Sept. 14, 1915.

Application filed May 8, 1913. Serial No. 766,449.

To all whom it may concern:

Be it known that we, LELAND F. JOHNSON and ANDREW D. WYCKOFF, citizens of the United States, residing at Fort Wayne, in the county of Allen and State of Indiana, have invented certain new and useful Improvements in Waste-Soaking Tanks, of which the following is a specification.

This invention relates to a tank of the class described, which is provided with means for holding a quantity of waste and for soaking the same in liquid and for draining waste of surplus liquid.

The principal object of the invention is to provide a new and improved tank of this class which is simple and compact in construction and effective and efficient in operation.

For the attainment of these ends and the accomplishment of other new and useful objects, as will appear, the invention consists in the features of novelty in the construction, combination and arrangement of the several parts generally shown in the accompanying drawings and described in the specification but more particularly pointed out in the appended claims.

In the accompanying drawings: Figure 1 is a side elevation, with sections broken away, of a waste soaking tank embodying the principles of our invention; Fig. 2 is a plan view of one of the screens for the waste soaking compartment; Fig. 3 is a side elevation of the tank showing a T in cross section; Fig. 4 is a detail view, partly in section, of the operating valve, and Fig. 5 is a plan view of the tank with the pump, valve and covers removed.

It is customary to pack axles, shafts and bearings with waste soaked in oil for the purpose of lubrication. The present invention is designed to provide a suitable waste soaking, holding and draining receptacle in which the waste is ready for immediate use at all times, and also to provide means whereby the oil for soaking the waste may be used repeatedly with the greatest economy and facility.

A receptacle 10 is provided, preferably constructed of sheet metal and rectangular in form with an open top. As the receptacle is of suitable length it is usually provided with braces 11 for strengthening the sides thereof. Disposed in the receptacle transversely thereof are channel members 12

forming braces for a partition member 13 extending from one end of the receptacle at a distance above the bottom thereof to a point intermediate of the ends thereof where it is bent upwardly forming two separate chambers 14 and 15 in the receptacle above the bottom thereof. The compartment 14 is therefore a closed compartment and is adapted to contain liquid and it is preferably designated as a "waste soaking compartment." The bottom of this compartment is preferably inclined slightly toward the end of the receptacle so that liquid will gravitate therein, and in the lower end of the compartment the member 13 is provided with an opening 17 in which is disposed a spider member 18 forming a valve seat in the opening and having a threaded hub portion 19 concentric with the opening. Threaded through the hub 19 is a correspondingly threaded end of a valve stem 20 upon which is secured a valve member 21 adapted to coöperate with the valve seat of the spider member. The upper end of the stem 20 is disposed adjacent but below the upper edge of the receptacle and is provided with a hand wheel 22. In order to steady the upper end of the stem a perforated guide 23 is secured to the receptacle, and a collar 24 is adjustably secured to the stem adjacent the guide 23 to limit the upward movement of the stem whereby it cannot be entirely withdrawn from the threaded hub 19.

In the bottom of the compartment 14 a false bottom 25 is disposed so that any oil in the compartment may be free to gravitate toward the lower end thereof. Adjacent the lower end of the compartment the bottom is provided with stops 26, and disposed against the stops are a plurality of screens 27. These screens are preferably formed with a recess portion 28, as shown more clearly in Fig. 2, by means of which the screen may be placed over the valve opening 17 and about the stem of the valve to prevent any waste from escaping through the valve opening into the oil storage compartment below the compartment 14, and for preventing the waste from clogging the valve. A plurality of these screens 27 are preferably provided and they are disposed at different inclinations to the bottom of the compartment so that they may form an effectual stop for waste in the compartment.

The compartment 15 is preferably desig-

nated as the "waste draining compartment", and around the lower edges of this compartment it is provided with supporting members 16. Disposed upon the supporting members is a screen 29 which is preferably provided with cross braces 30. In one corner of the compartment 15 a tube 31 is secured in any suitable means, as, for example, by means of a collar 32, the upper end of 10 the tube being located just below the upper edge of the receptacle and the tube extending through the screen 29 to a point adjacent the bottom of the receptacle. In this tube a measuring rod 33 is disposed by means 15 of which the height of oil in the receptacle can easily be determined at all times.

The top of the receptacle is covered by means of lids 34 and 35 which are either separately removable or separately hinged, 20 as shown, and are preferably adapted to cover each of the separate compartments so that access may be had to either of the compartments separately.

Secured to one side of the receptacle is a support 36 upon which a pump, designated generally by the reference character 37, is mounted, and a stop cock 38 to which is connected a T 39 for connection between the pump and the receptacle 10 adjacent the 25 bottom thereof. The T is provided with a plug 40 and disposed within the T is a removable screen 41 to prevent any waste which may have gotten into the bottom of the receptacle from being drawn into the 30 pump. The stop cock is provided so that it may be closed and the pump bodily removed for cleaning or repair without emptying the receptacle of the liquid contained 35 therein. The discharge nozzle of the pump 40 is disposed above the waste soaking compartment so that when the lid 34 is raised, as shown in Fig. 3, the pump will discharge 45 directly into the compartment. The receptacle 10 is also provided with a clean-out plug 42 at one end thereof.

In operation, a quantity of waste is placed in the waste soaking compartment 14 and a quantity of liquid is pumped from the bottom of the receptacle into the waste soaking 50 compartment until all of the waste, or as much of it as desired, is saturated with the liquid. The valve at the end of the compartment is closed under these circumstances but may be opened to allow the escape of oil therefrom 55 and to drain the compartment when desired. The waste may be used directly from the waste soaking compartment, or, if desired, some of it may be placed in the waste draining compartment 15, which, having a reticulated bottom, will permit any surplus liquid 60 to drain therefrom into the compartment at the bottom of the receptacle. Wholly or partially saturated waste is thus at immediate disposal. It is obvious that

the waste may be used repeatedly and that 65 the oil for saturating the waste may also be used repeatedly. The valve and pump are screened to prevent the waste from clogging them. The valve may be operated 70 from the top of the soaking receptacle when the lid 34 is raised, and the height of oil in the receptacle may be determined by simply raising the rod 33 out of the tube 31 when the lid 35 of the waste draining compartment is raised.

75 What we claim is:

1. A waste soaking tank having a partition which forms an oil storage compartment at the bottom, and a waste soaking and waste draining compartment over the storage compartment with a common partition separating them, the walls of the tank forming the walls of the compartment.

80 2. A waste soaking tank having a partition which forms an oil storage compartment at the bottom, a waste soaking compartment having closable communication through its bottom with the storage compartment, and a waste draining compartment with a screen which separates it from 85 the storage compartment into which it freely drains.

90 3. A waste soaking tank having a partition which forms an oil storage compartment at the bottom and a waste soaking 95 compartment and a draining compartment above the storage compartment completely filling the upper portion of the tank, the draining compartment being provided with a removable screen separating it from the 100 storage compartment, and a valve in the partition between the soaking compartment and the oil storage compartment.

105 4. In a waste soaking tank a receptacle forming an oil storage chamber in the bottom thereof, and a single partition member forming both an inclined waste soaking compartment and a waste draining compartment 110 above the oil storage compartment in the receptacle.

115 5. In a waste soaking tank, the combination with a receptacle forming an oil storage compartment in the bottom thereof, of a single partition forming an inclined compartment and a draining compartment which fill the receptacle above the oil storage compartment, the compartment having common outer walls.

120 6. In a waste soaking tank, the combination with a receptacle forming an oil storage compartment in the bottom thereof, of a partition member forming an inclined compartment and a draining compartment which fill the receptacle above the oil storage compartment, all of the compartments having common outer walls and separate hinged covers for both of said upper compartments.

7. In a waste soaking tank, the combination with a receptacle for forming an oil storage compartment in the bottom thereof, of a single partition member for forming a 5 waste soaking compartment and a separate waste draining compartment above the oil storage compartment, and a perforated screen in the bottom of the waste draining compartment separating it from the storage 10 compartment.

8. In a waste soaking tank, the combination with a receptacle, of a partition forming a waste soaking compartment therein spaced from the bottom of the compartment, 15 and forming part and parcel of the receptacle and a valve forming communication between the upper compartment and the space at the bottom of the receptacle.

9. In a waste soaking tank, the combination with a receptacle, of means within the receptacle and integral therewith forming an inclined compartment with its bottom spaced above the bottom of the receptacle and inclined toward one end thereof, and a 25 valve disposed at the lower end of the compartment forming communication between the compartment and the bottom space in the receptacle and operable from the top of the upper compartment.

30 10. In a waste soaking tank, the combination with a receptacle, of means forming a compartment in the receptacle spaced from the bottom thereof, a valve forming communication between the compartment and the 35 chamber at the bottom of the receptacle, said valve being disposed entirely within the receptacle and having means extending through the upper compartment to the top of the receptacle for operating the valve, 40 and a lid for the receptacle above the valve operating means.

11. In a waste soaking tank, the combination with a receptacle, of a compartment therein with its sides in common with the receptacle sides and with its bottom spaced above the bottom of the receptacle, and having a perforation in the bottom, a threaded spider member secured to the bottom of the compartment concentric with the opening 50 therein, a threaded rod movable in the spider having an extremity adjacent the top of the compartment, and a member secured to the rod adapted to open and close the opening when the threaded rod is correspondingly 55 rotated.

12. In a waste soaking tank, a waste soaking compartment, a valve in the bottom at one end thereof, and removable reticulated members disposed at the end of the compartment and at an inclination over the valve.

60 13. In a waste soaking tank, the combination with a receptacle, of means forming a waste soaking compartment therein above the bottom of the receptacle, a valve at one

end of the compartment having an upwardly 65 extending valve stem, and screens extending across the compartment at the end thereof and adapted to extend over the valve and around the valve stem.

14. In a waste soaking tank, the combination with a receptacle, of means forming a compartment in the receptacle above the bottom thereof inclined toward one end thereof, a valve in the bottom of the compartment at the lower end having an upwardly 70 extending operating stem, and screens removably disposed above the valve about the stem at different inclinations to the bottom of the receptacle.

15. In a waste soaking tank, the combination with a receptacle, of means forming a waste soaking compartment above the bottom of the receptacle, having its sides in common with the receptacle sides, a valve 80 forming communication between the bottom 85 of the compartment and the space at the bottom of the receptacle, and a pump connected with the bottom of the receptacle discharging into the waste soaking compartment.

16. In a waste soaking tank, the combination with a receptacle, of means forming a waste soaking and waste draining compartment therein spaced above the bottom of the receptacle, a screen in the bottom of the waste draining compartment, a tube secured 90 to the receptacle and extending through the screen in the waste draining compartment from a point below the top of the receptacle to a point spaced from the bottom thereof, a measuring rod in the tube, and a removable 95 cover for the receptacle extending when closed over the top end of the tube.

17. In a waste soaking tank, the combination with a receptacle, of means forming an oil storage compartment therein spaced from the bottom of the receptacle and part and parcel of the receptacle construction, a valve in the bottom of the compartment, a pump connected to the bottom of the receptacle and discharging directly into the upper compartment, and a stop cock disposed between the pump and the receptacle whereby the pump may be disconnected therefrom for 105 cleaning.

18. In a waste soaking tank, the combination with a receptacle, of a partition forming both a waste soaking and a separate waste draining compartment therein spaced above the bottom of the receptacle and forming a bottom storage compartment, a 110 valve in the bottom of the waste soaking compartment, a screen in the bottom of the waste draining compartment, separating it from the storage compartment, means preventing the contact of waste in the waste 115 soaking compartment with the valve therein, a stop cock at the bottom of the receptacle, a T connected to the stop-cock, a screen re-

movably disposed in the **T**, and a pump connected to the **T** adapted to discharge liquid from the bottom of the storage compartment into the top of the waste soaking compartment.

5 In testimony whereof we have signed our names to this specification, in the presence of

two subscribing witnesses, on this 24th day of April A. D. 1914.
